UNITED STATES PATENT OFFICE.

WILLIAM H. McDONALD, OF TITUSVILLE, PENNSYLVANIA.

DESIGN FOR A GARDEN-HOE.

SPECIFICATION forming part of Design No. 32,228, dated February 13, 1900.
Application filed December 15, 1899. Serial No. 740,475. Term of patent 7 years.

To all whom it may concern:

Be it known that I, WILLIAM H. McDONALD, a citizen of the United States of America, residing at Titusville, in the county of Crawford and State of Pennsylvania, have invented a certain new and useful Design for a Garden-Hoe, of which the following is a specification, reference being had therein to the accompanying drawing.

10 My invention relates to certain new and novel designs in garden-hoes.

The design consists of the novel outline and configuration set forth in the accompanying drawing.

15 In describing the design in detail reference is had to the accompanying drawing, forming a part of this specification and wherein like numerals of reference indicate like parts in the view, which illustrates a perspective view of my new and novel design for a garden-hoe.

20 Referring to the drawing by reference-numerals, 1 indicates the handle, substantially rectangular in cross-section and which projects on a horizontal line from the hoe-blade 2 and has the sides thereof tapering toward its free end. The hoe-blade 2 is flat and substantially rectangular in contour and has its upper edge formed into a pair of curves 3, each inner end thereof meeting each other 30 centrally of the hoe-blade. The side edges of the hoe-blade at their lower portion converge inwardly, as at 6.

5 indicates a series of inverted curvilinear V-shaped slits, the sides of which meet at 35 their upper end and form a point and at their lower end converge outwardly and in connection with the lower curved ends of the sides form a series of flat curvilinear pointed prongs.

Having thus described my invention, what I claim as new, and desire to secure by Letters Patent, is—

The design for a garden-hoe, substantially as herein shown and described.

25 In testimony whereof I affix my signature in the presence of two witnesses.

WILLIAM H. McDONALD.
